CLAIM

The ornamental design for a paint brush and roller drying and storage system, as shown and described.

DESCRIPTION

FIG. 1 shows a perspective view of my design for a paint brush and roller drying and storage system;

FIG. 2 shows a top view thereof;

FIG. 3 shows a first side view thereof;

FIG. 4 shows a second side view thereof;

FIG. 5 shows a bottom view thereof; and,

FIG. 6 shows a side view of my design for a paint brush and roller drying and storage system sitting in a bucket in an intended use of the system.

The elements shown in broken lines depict environmental structure only and form no part of the claimed design.
